Des. 186,960
Patented Dec. 29, 1959

186,960

SCINTILLATION SCANNING APPARATUS

Roland W. Carlson, East Cleveland, and Clarence E. Lemmermann, Cleveland, Ohio, assignors to Picker X-Ray Corporation, Waite Mfg. Div., Inc., Cleveland, Ohio, a corporation of Ohio

Application May 11, 1959, Serial No. 55,857

Term of patent 14 years

(Cl. D61—1)

FIG. 1

FIG. 2

Figure 1 is a front perspective view of a scintillation scanning apparatus, showing our new design; and,

Figure 2 is a rear perspective view thereof, with adjustable parts in a slightly different position.

We claim:

The ornamental design for a scintillation scanning apparatus, as shown.
